 NEW ORGANIC PHOSPHORUS COMPOUNDS AND
THEIR MANUFACTURE AND USE

 Ernest Beriger, Alischwil, Switzerland, assignor to
Ciba Limited, Basel, Switzerland

 No Drawing. Filed Oct. 21, 1957, Ser. No. 691,163
Claims priority, application Switzerland Oct. 25, 1956
10 Claims. (Cl. 269—461)

This invention provides new organic phosphorus compounds of the general formula

in which R, R₁ and R₂ represent alkyl, cycloalkyl, aralkyl, aryl or heterocyclic residues which may contain substituents, and of which R and R₁ may together form part of a ring system, R₃ represents hydrogen or an alkyl residue or a halogen atom, R₄ represents an alicyclic, aromatic or heterocyclic residue, X and Y represent —O—, —S—, —NH— or

and Z represents oxygen or sulfur, and n and m each represent the whole number 1 or 2 or compounds of the general formula

in which R, R₁, R₂, R₃, X, Y, Z and n and m have the meanings given above.

It has not yet been ascertained with certainty which of the above Formula I and II should be accorded to the compounds of this invention. It is probable that, depending on the method of preparation, the compounds have only one or other of these formulae or compounds of one of the formulae are preferentially formed. It is known that in the reaction of trialkyl phosphites with certain halogen-compounds in accordance with the Michaelis-Arbuzow reactions rearrangements occur so that instead of the expected phosphonic acid derivatives the isomeric phosphoric acid esters are formed. In the present invention, for example, the condensation product of $\alpha:\alpha$ -dichlorobenzoylacetic acid ethyl ester with trimethyl phosphite can be given the following formulae

The invention therefore includes compounds of the above Formulae I and II and also any mixtures of these compounds, since the isomerism of the compounds can be considered as keto-enol tautomerisms. Accordingly, when one form is given in this specification it is to be understood that the other form is included, provided that that form is capable of existing.

2

The new compounds are valuable agents for combating pests, especially animal pests. They are active against the various stages of development, such as eggs, larvae and imagines, so that they are both contact and stomach poisons. Suitably substituted compounds of this invention exhibit an inner-therapeutic, so-called systemic, action when applied to plants. Especially valuable are compounds of the general formulae

in which R, R₁ and R₂ represent lower alkyl residues containing 1—4 carbon atoms, R₃ represents a hydrogen atom or a chlorine atom, and R₄ represents a cyclohexyl, phenyl, furyl or tetrahydrofuryl residue which may contain substituents.

The compounds of this invention can be obtained by condensing a compound of the formula

in which R, R₁, n, m, X, Y and Z have the meanings given above, and R₅ represents a lower alkyl residue containing 1—4 carbon atoms, with a compound of the formula

in which R₂, R₃ and R₄ have the meanings given above, and Hal represents a halogen atom, such as bromine or preferably chlorine, the condensation taking place with the splitting off of a compound of the formula R₅-Hal.

The new compounds can also be obtained by reacting a compound of the formula

in which R, R₁, n, m, X, Y and Z have the meanings given above, and Me represents an alkali metal, advantageously sodium, with a compound of the formula

in which R₂, R₃, R₄ and Hal have the meanings given above. For preparing those compounds in which R₃ represents a hydrogen atom or an alkyl residue, the following condensation may be carried out:

The choice of one or other of the reactions mentioned

above, depends on the accessibility of the starting materials.

The compounds of the general formula

which may be used as starting materials are derivatives of trivalent phosphorus, whereas the products of the invention are derivatives of pentavalent phosphorus.

Among the compounds of the formula last given above the most easily accessible are those in which the symbols X, Y and Z represent oxygen. They correspond to the formula

and can be obtained by methods in themselves known.

The aliphatic residues, which the symbols R and R₁ may represent, may have straight or branched chains and may be saturated or unsaturated. They may be substituted or unsubstituted. There may be mentioned, for example, methyl, ethyl, propyl, isopropyl, butyl, hexyl, 2-ethylbutyl, octyl, 2-butyloctyl, dodecyl, octadecyl, allyl and 2-chloroethyl groups, and also radicals containing thiocyanato, cyano or ester groups. The residues R and R₁ may be identical or different from one another. R₅ is advantageously a lower alkyl residue containing 1-4 carbon atoms.

There may be mentioned, for example, the following compounds:

Trimethylphosphite, triethylphosphite, tripropylphosphite, diethyl-dodecylphosphite, tri-(2-chloroethyl)-phosphite and the ester of the formula

The aromatic radicals, which R and R₁ may represent, may be mononuclear or polynuclear, and may contain nuclear substituents. There may be mentioned, for example, phenyl, 2- or 4-chlorophenyl, 2:4-dichlorophenyl, 4-methoxyphenyl, 4-nitrophenyl, naphthyl and 4-diphenyl groups. Thus, compounds such as 2:4-dichlorophenyl diethylphosphite and 4-chlorophenyl dimethyl phosphite may be mentioned. There may also be mentioned compounds in which one or two residues are bound directly by a carbon atom to the phosphorus atom, for example, phenyl-phosphorous acid diethyl ester of the formula

Among araliphatic radicals, which R and R₁ may represent, there may be mentioned the benzyl radical, among the cycloaliphatic radicals the cyclohexyl radical, and among the heterocyclic radicals the tetrahydrofurfuryl radical. Starting materials containing such radicals are, for example, cyclohexyl diethylphosphite, tetrahydrofurfuryl dimethylphosphite and dibenzylpropylphosphite. Among compounds in which X and Y represent sulfur there may be mentioned triethylthiophosphite of the formula

and among those in which X and Y represent nitrogen, the compound of the formula

The compounds of the general formula

5

are salts of disubstituted phosphites or phosphinic acids for example, sodium salts of dimethylphosphite, diethylphosphite, dodecylethylphosphite, cyclohexylmethylphosphite, tetrahydrofurfurylthiophosphite or benzyl ethyl phosphite.

10 The compounds of the general formula

15

are phosphoric acid monohalides, for example, phosphoric acid diethylester monochloride, thiophosphoric acid diethylester monochloride or bis-(dimethylamido)-phosphoric acid monochloride.

20 The compounds of the general formula

25

are esters of halogenated acylacetic acids derived from alicyclic aromatic or heterocyclic carboxylic acids advantageously benzoyl-, hexahydrobenzoyl-, furoyl- or tetrahydrofuroylacetic acid. The residue R₂ may have the meanings given above for the residues R and R₁. Advantageously it consists of a lower alkyl group containing 1-4 carbon atoms.

30

The residue R₃ may be a halogen atom, advantageously a chlorine atom, or a hydrogen atom or an alkyl residue advantageously containing 1-4 carbon atoms, such as the methyl group. R₄ may be a

35

heterocyclic residue, such as the furyl residue or tetrahydrofuryl residue, an aryl residue, for example, the phenyl, chlorophenyl, nitrophenyl group, or a cycloalkyl residue, such as the cyclohexyl group. Among the reaction components of the formula last mentioned above

40

there may be mentioned, $\alpha:\alpha$ -dichlorobenzoyl-acetic acid ethyl ester, $\alpha:\alpha$ -dichlorobenzoyl-acetic acid methyl ester, $\alpha:\alpha$ -dichloro-4-chlorobenzoyl-acetic acid methyl ester, α -chloro-4-nitro-benzoyl-acetic acid methyl ester, $\alpha:\alpha$ -dichlorofuroyl-acetic acid ethyl ester and $\alpha:\alpha$ -dichlorohexahydrobenzoyl-acetic acid methyl ester.

45

In order to prepare the products of this invention the reaction components are heated together at a raised temperature, for example, within the range of 50-200°C., and advantageously about 90-150°C. It may be of advantage or convenient to work in an inert solvent, such as benzene, toluene, xylene, chlorobenzene or benzine and, if desired in an atmosphere of an inert gas, for example, under nitrogen, and/or under reduced pressure.

50

As stated above, the products of this invention are valuable agents for combating pests. Accordingly, the invention also provides preparations for combating pests, which contain a product of the invention as active substance, and a process for combating pests with such preparations.

60

Especially advantageous are compounds of the general formula

65

in which R, R₁ and R₂ represent alkyl residues containing 1-4 carbon atoms, R₃ represents a hydrogen atom or a chlorine atom, and R₄ represents a cyclohexyl, phenyl, furyl or tetrahydrofuryl group which may contain substituents.

A very wide variety of materials can be protected against pests, and gaseous, liquids or solid materials may

be used as carriers for the active substances. As materials to be protected or to be used as carriers there may be mentioned, for example, air, especially in rooms, and liquids, for example, water in ponds, and any non-living or living solid substratum, for example, any objects in living rooms, in cellars, in plaster, floors, stables, and also pelts, feathers, wool or the like, and living organisms of the vegetable and animal kingdom at all stages of development, so far as they are not sensitive to the pest combating agent.

The compounds are used for combating pests by the usual methods, for example, by treating the material to be protected with the compound in the formula of vapour, for example, in the form of a fumigating preparation or in the form of a dusting powder or spraying liquor, for example, in the form of a solution or suspension, which may be prepared with water or a suitable organic solvent, for example, alcohol, petroleum, tar distillates or the like. Aqueous solutions of the active substances or aqueous emulsions of organic solvents containing the active substances, may be used for coating, spraying or immersing the objects to be protected.

The spraying preparations or dusting powders may contain the usual inert fillers or identifying agents, for example, kaolin, gypsum or bentonite or other additions, such as sulfite cellulose waste liquor, cellulose derivatives or the like, and also the usual wetting agents or adherent agents for improving the wetting capacity and adherence of the preparations. The pest combating preparations may be made up in powdered form or in the form of aqueous dispersions or pastes or as self-dispersing oils.

The preparations may contain compounds of the invention as the sole active substances or in admixture with other insecticides and/or fungicides. Such preparations may be used for the protection of plants by the usual spraying, pouring, dusting or fumigating methods.

The following examples illustrate the invention, the parts and percentages being by weight unless otherwise stated, and the relationship of parts by weight to parts by volume being the same as that of the kilogram to the liter:

Example 1

A solution of 13.05 parts of $\alpha:\alpha$ -dichlorobenzoyl-acetic acid ethyl ester (boiling at 110° C. under 0.008 mm. pressure) in 15 parts by volume of chlorobenzene is heated to the boil. 6.8 parts of trimethyl phosphite are added dropwise in the course of 5 minutes, and the reaction is completed by boiling the mixture for one hour under reflux. 2.1 parts of methyl chloride are collected. By evaporating the volatile constituents at 95° C. under reduced pressure produced by a water jet pump there is obtained as residue 15.9 parts of a bright yellow oil, which dissolves well in acetone and alcohol and scarcely dissolves at all in water.

Example 2

A solution of 13.05 parts of $\alpha:\alpha$ -dichlorobenzoyl-acetic acid ethyl ester in 15 parts by volume of chlorobenzene is heated to the boil and 9.1 parts of triethylphosphite are added dropwise in the course of 5 minutes. The initially vigorous evolution of ethyl chloride is completed by boiling for one hour under reflux. The solvent and the excess of triethyl phosphite are removed in vacuo at 95° C. The residue (18.8 parts) is an oily liquid which boils at 168° C. under 0.3 mm. of mercury.

Example 3

A solution of 12.35 parts of $\alpha:\alpha$ -dichlorobenzoyl-acetic acid methyl ester (boiling at 100–102° C. under 0.2 mm. pressure) in 13 parts by volume of chlorobenzene is heated to the boil and 6.8 parts of trimethyl phosphite are added dropwise in the course of 5 minutes. In order to complete the reaction the mixture is maintained at the boil for a further hour. The volatile constituents are then removed in vacuo at 95° C., and there is obtained a resi-

due consisting of 16.7 parts of a very mobile oil, which dissolves in acetone and isopropyl alcohol, and which boils at 154–158° C. under 0.04 mm. pressure.

Example 4

To a mixture of 12.35 parts of $\alpha:\alpha$ -dichlorobenzoyl-acetic acid methyl ester and 13 parts by volume of chlorobenzene at the boiling temperature there are added dropwise 9.1 parts of triethyl phosphite. When the addition is complete, the solution is maintained at the boil for a further hour. The solvent and volatile constituents are then removed in vacuo at a bath temperature of 95° C. There is obtained as residue a bright yellow oil, which is soluble in acetone and isopropyl alcohol.

Example 5

A mixture of 14.07 parts of $\alpha:\alpha$ -dichloro-para-chlorobenzoyl-acetic acid methyl ester (boiling at 121–129° C. under 0.2 mm. pressure) and 15 parts by volume of chlorobenzene is mixed dropwise at the boil with 6.82 parts of trimethyl phosphite. When the dropwise addition of the trimethyl phosphite is complete, the solution is maintained at the boil for a further hour. At the end of this period 2.4 parts of methyl chloride will have been collected in the receiver cooled with Dry Ice and acetone. The volatile constituents are removed in vacuo, and there are obtained as residue 18.4 parts of a thickly liquid oil, which is easily soluble in acetone and isopropyl alcohol.

Example 6

14.07 parts of α -monochloro-ortho-chlorobenzoyl-acetic acid methyl ester in 16 parts by volume of chlorobenzene are heated to the boil. 6.8 parts of trimethyl phosphite are added dropwise, and the reaction is completed by boiling the mixture for a further $\frac{1}{2}$ hour. After distilling off the volatile constituents in vacuo, there are obtained 16.9 parts of a poorly mobile oil, which is soluble in acetone and isopropyl alcohol.

Example 7

12.87 parts of α -chloro-para-nitrobenzoyl-acetic acid methyl ester (melting at 106–107° C.) and 13 parts by volume of chlorobenzene are heated to the boil, and 6.8 parts of trimethyl phosphite are added dropwise. The mixture is boiled under reflux for a further hour to complete the reaction. The volatile constituents are then removed in vacuo at a bath temperature of 95° C. The residue is a yellow oil (16.85 parts) which is easily soluble in isopropyl alcohol and acetone.

Example 8

7.45 parts of triethyl phosphite are added in the course of 5 minutes to a mixture of 10.5 parts of α -chloro-para-nitrobenzoyl-acetic acid methyl ester and 12 parts by volume of chlorobenzene maintained at the boil. When the addition is complete, the reaction mixture is boiled under reflux for a further hour, and then the solvent and excess of phosphite are removed in vacuo at a bath temperature of 95° C. The residue is a yellow oil (14.8 parts), which dissolves well in alcohol and acetone.

Example 9

12.55 parts of $\alpha:\alpha$ -dichlorofuroyl-acetic acid ethyl ester are diluted with 15 parts by volume of chlorobenzene. The mixture is brought to the boil, and 6.8 parts of trimethylphosphite are added. After boiling the mixture under reflux for $\frac{1}{2}$ hour 2.2 parts of methyl chloride are collected. The volatile constituents are removed at 95% C. under the reduced pressure of a water jet pump, and the residue consists of 14.1 parts of a very mobile oil, which dissolves in acetone and isopropyl alcohol.

Example 10

A solution of 12.6 parts of $\alpha:\alpha$ -dichloro-hexahydrobenzoyl-acetic acid methyl ester (boiling at 102–103° C.

under 0.12 mm. pressure) in 15 parts by volume of chlorobenzene is heated to the boil and 6.8 parts of trimethyl phosphite are added dropwise in the course of 5 minutes. In order to complete the reaction the mixture is heated under reflux for a further hour. The volatile constituents are then removed in vacuo at a bath temperature of 95° C., and the residue consists of an almost colorless thinly liquid oil (15.5 parts), which is soluble in acetone and isopropyl alcohol.

In an analogous manner the halogenated β -keto-acid esters set out in the following table can be reacted with tertiary phosphite. Only some of the resulting esters, of which the properties are also given in the table, can be distilled in a high vacuum without decomposition. However, for making pest combating preparations it is unnecessary to purify the compounds by distillation.

5 to the mixture in the course of 5 minutes. In order to complete the reaction the solution is maintained at the boil for a further hour. 1.8 parts of ethyl chloride distil off. The xylene and small amount of volatile constituents are removed in vacuo at a bath temperature of 95° C. The residue consists of 18.5 parts of a bright thinly liquid oil, which dissolves very well in alcohol and acetone.

Example 12

10 13.05 parts of dichlorobenzoyl-acetic acid ethyl ester are heated to 150-160° C. and 11.1 parts of diethyl tetrahydrofurfuryl phosphite,

(boiling at 59° C. under 0.4 mm. pressure) are added

No.	β -Keto-ester	Halogenated β -keto-ester	Phosphite components and properties of their esters
1-2	—COCH ₂ COOCH ₃ . B.P. 103° C. (0.08 mm.).		(CH ₃ O) ₃ P easily mobile oil. B.P. 167.5-169° C. (0.07 mm.).

Example 11

13.05 parts of dichlorobenzoyl-acetic acid ethyl ester in 15 parts by volume of xylene are heated to the boil, and 12.2 parts of diethyl allyl phosphite

(boiling at 64-66° C. under 12 mm. pressure) are added

70 dropwise in the course of 5 minutes. The mixture is maintained for a further hour at 170-180° C. 2 parts of ethyl chloride are collected. The volatile constituents are removed in vacuo at 180° C., and the residue consists of 20.8 parts of an easily mobile oil, which dissolves well in alcohol and acetone.

In an analogous manner the following phosphites can be reacted with dichlorobenzoyl-acetic acid ethyl ester.

Phosphite	Reaction temperature, ° C.	Reaction product
$(C_2H_5O)_2P-O-CH_2-\text{C}_6H_4-$ ...	180-210	Easily mobile oil, soluble in alcohol, acetone.
B.P. 84° C. (0.3 mm.).		
$(C_2H_5O)_2P-O-\text{C}_6H_4-$ ...	180	Bright, thinly liquid oil soluble in alcohol, acetone.
B.P. 50° C. (0.3 mm.).		
$(C_2H_5O)_2P-O-\text{C}_6H_4-Cl-$ ...	180	Easily mobile oil, soluble in alcohol, acetone.

Example 13

13.05 parts of dichlorobenzoyl-acetic acid ethyl ester are heated to 150-160° C., and 6.8 parts of ethyl ethylene phosphite

(boiling at 49° C. under 10 mm. pressure) are added dropwise. The mixture is slowly heated to 215° C. and maintained at that temperature for a further $\frac{3}{4}$ hour. 0.9 part of ethyl chloride is collected. The reaction does not take place solely with the splitting off of ethyl chloride, but partially involves splitting up of the ethylene phosphite ring. The easily volatile constituents are removed in vacuo at 180° C., and the residue is an easily mobile oil (17.8 parts), which dissolves well in alcohol and acetone and hardly at all in water.

Example 14

9.65 parts of O-diethyl-N-diethylamido-phosphite ($C_2H_5O)_2PN(C_2H_5)_2$ are added in the course of 5 minutes to a mixture of 13.05 parts of dichlorobenzoyl-acetic acid ethyl ester and 15 parts by volume of chlorobenzene at the boil. In order to complete the reaction the mixture is maintained for a further hour at the boil. 2.5 parts of ethyl chloride distil over. The solvent is removed in vacuo at a bath temperature of 95° C. The residue is a bright easily mobile oil (18.6 parts), which dissolves well in alcohol and acetone.

Example 15

9.9 parts of phenyl-phosphonous acid diethyl ester

(boiling at 108–114° C. under 10 mm. pressure) are added dropwise to a mixture of 13.05 parts of dichlorobenzoyl-acetic acid ethyl ester with 15 parts by volume of chlorobenzene, the mixture being heated to the boil. The reaction is finished in the course of 3/4 hour, and 2.0 parts of ethyl chloride are collected. After removing the xylene in vacuo there are obtained 19.3 parts of a thinly liquid oil which dissolves well in alcohol and acetone.

Example 16

21.4 parts of the sodium salt of benzoyl-acetic acid ethyl ester are stirred well in 50 parts by volume of chlorobenzene. Beginning at 20° C. 18.9 parts of diethyl thiophosphoric acid ester chloride are added dropwise in the course of 20 minutes while stirring, the temperature being raised to 30° C. The mixture is allowed to react completely overnight at 50–60° C. After being cooled, the solution is washed three times with a small amount of water, dried over sodium sulfate, and then the solvent

is removed in vacuo. The residue consists of 25.8 parts of a mobile oil, which dissolves well in alcohol and acetone.

Example 17

- 5 2 parts of the condensation product obtained as de-
scribed in Example 1 or 2 are mixed with 1 part of the
condensation product of 1 mol of tertiary octyl phenol
and 8 mols of ethylene oxide, and 7 parts of isopropanol.
10 There is obtained a clear solution which can be used
as a concentrate for making up spray liquors and emulsi-
fies when poured into water.
15 (A) In order to demonstrate the contact action on
aphids the following experiments were carried out. Spraying
liquors were used at concentrations of active substance
of 0.08%, 0.04% and 0.02%.
20 Broad beans, which were heavily infected with aphids,
were sprayed from all sides and the effect was examined
after 48 hours. The plants on which the action was 100%
were infected with fresh aphids, and the action was ex-
amined after a further 48 hours. The results obtained are
given in the following table:

Spray liquor con- centration, percent	Action on aphids				
	After 48 hours		48 hours after reinfection		
	Example 1	Example 2	Example 1	Example 2	
0.08	++	++	++	++	
0.04	++	++	++	++	
0.02	++	++	--	--	

- 35 For each plant a mark is used. + means that no living aphids are present, ' means a good action, only a few aphids alive, and - means an insufficient or no action.

- (B) In order to demonstrate the action on aphids by diffusion through the leaves the following experiment was carried out, with the use of a spray liquor containing 0.08% of active substance.

Broad beans, which were infected with aphids only on the undersides of the leaves, were sprayed with the above liquor only on the upper surfaces of the leaves, and after 48 hours the action on the aphids under the leaves was examined. The results obtained are given in the following table:

Spray liquor concentration, percent	Action of aphids Example 1
0.08	++

- 55 (C) In order to demonstrate the action of the compounds of Examples 1 and 2 as stomach poisons, leaves were immersed in spray liquors containing 0.04% of the active substance. When dry the leaves were fed to locusts.

- After a few days the locusts were killed. The compounds of Examples 1 and 2 also exhibit a good action against the eggs of *Ephestia kuhniella*. They may be used in dormant spray preparations as active substances against the wintering stages of pests.

- For preparing the spray concentrates there may be used wetting and emulsifying agents other than those mentioned above. There may be used non-ionic products, for example, condensation products of aliphatic alcohols, amines or carboxylic acids containing a long-chain hydrocarbon radical of about 10-30 carbon atoms with ethylene oxide, such as the condensation product of octadecyl alcohol with 25-30 mols of ethylene oxide, or the condensation products of soya bean fatty acid with 30 mols of ethylene oxide, or that of commercial oleylamine with 15 mols of ethylene oxide, or that of dodecyl mercaptan

11

with 12 mols of ethylene oxide. Among the anion-active emulsifying agents, which may be used, there may be mentioned the sodium salt of dodecyl alcohol sulfonic acid ester, the sodium salt of dodecylbenzene sulfonic acid, the potassium or triethanolamine salt of oleic acid or abietic acid, or a mixture of these acids, or the sodium salt of a petroleum sulfonic acid.

Instead of isopropanol there may be used other solvents for making up the spray concentrates, for example, ethyl alcohol, methanol, butanol, acetone, methyl ethyl ketone, methyl-cyclohexanol, benzene, toluene, xylene, kerosene or petroleum fractions. There may, of course, be used mixtures of these solvents.

Example 18

2 parts of the product of Example 2 are mixed with 9 parts of chalk and 1 part of a wetting agent. There is obtained a spray powder, which can be used for making spray liquors by suspending it in water. By treating the walls of stables with such a spray liquor containing 0.4% of active substance, good results are obtained against flies and gnats.

Example 19

1 part of the product of Example 2 is mixed with 99 parts of talc. The resulting mixture is an insecticidal dusting powder, which is suitable for dusting vines to combat *Pyralis* caterpillars and *Conchyliis* caterpillars. The talcum may be replaced wholly or in part by sulfur, in which case the preparation is also active against *Oidium*. Instead of talc, other pulverulent carriers may be used, such as chalk, bentonite, kaolin or mixtures thereof.

such as shark, conger,

1. An organic phosphorus compound which is represented by one of the general formulae

and

wherein R and R_1 is each selected from the group consisting of an alkyl radical containing at most 18 carbon atoms, an allyl radical, a tetrahydrofurfuryl radical, a benzyl radical, a phenyl radical and a chlorophenyl radical; R_2 represents an alkyl radical containing at most 18 carbon atoms; R_3 represents a member selected from the group consisting of a chlorine atom and a bromine atom; R_4 represents a member selected from the group consisting of a phenyl radical, a chlorophenyl radical, a cyclohexyl radical, a furyl radical, a benzene radical which is substituted by a lower alkyl radical, a benzene radical which is substituted by a lower alkoxy radical, a benzene radical which is substituted by a nitro group and a benzene radical which is substituted by a nitro group and a halogen atom; X represents a member selected from the group consisting of an oxygen atom and the group

wherein R_5 represents a lower alkyl radical; Y represents 75

12

an oxygen atom, n and m each represents an integer of at most 2; and Z represents a member selected from the group consisting of an oxygen atom and a sulfur atom.

2. An organic phosphorus compound of the following formula

in which R , R_1 and R_2 each represents an alkyl radical containing 1 to 4 carbon atoms and R_4 is the phenyl radical.

3. An organic phosphorus compound of the formula

in which R , R_1 and R_2 each represents an alkyl radical containing 1 to 4 carbon atoms and R_4 is a chlorophenyl radical.

4. An organic phosphorus compound of the formula

45 in which R , R_1 and R_2 each represents an alkyl radical containing 1 to 4 carbon atoms and R_4 is a nitrophenyl radical.

5. An organic phosphorus compound of the formula

60 in which R , R_1 and R_2 each represents an alkyl radical containing 1 to 4 carbon atoms and R_4 is the furyl radical.

6. The compound of the formula

13

7. The compounds of the formula

8. The compounds of the formula

9. The compound of the formula

10. An insecticidal composition comprising an organic phosphorus compound selected from the class consisting of compounds of the formula

3,085,079

14

and compounds of the formula

5

10 wherein R and R₁ is each selected from the group consisting of an alkyl radical containing at most 18 carbon atoms, an allyl radical, a tetrahydrofurfuryl radical, a benzyl radical, a phenyl radical and a chlorophenyl radical; R₂ represents an alkyl radical containing at most 18 carbon atoms; R₃ represents a member selected from the group consisting of a chlorine atom and a bromine atom; R₄ represents a member selected from the group consisting of a phenyl radical, a chlorophenyl radical, a cyclohexyl radical, a furyl radical, a benzene radical which is substituted by a lower alkyl radical, a benzene radical which is substituted by a lower alkoxy radical, a benzene radical which is substituted by a nitro group and a benzene radical which is substituted by a nitro group and a halogen atom; X represents a member selected from the group consisting of an oxygen atom and the group

wherein R₅ represents a lower alkyl radical, Y represents an oxygen atom, m and n each represents an integer of at most 2; and Z represents a member selected from the group consisting of an oxygen atom and a sulfur atom; in admixture with an insecticidally inactive carrier.
